[57] CLAIM

The ornamental design for a disposable handle for a hospital surgery room light fixture or the like as shown and described.

DESCRIPTION

FIG. 1 is a top plan view of a disposable handle for a hospital surgery room light fixture or the like showing my new design;

FIG. 2 is a side elevational view, with the opposite sides being a mirror image thereof;

FIG. 3 is a side elevational view, with the handle shown in disassembled form thereof; and

FIG. 4 is a bottom plan view thereof.

Fig. 2.

Fig. 1.

Fig. 3.

Fig. 4.
